CLAIM

The ornamental design for a mower blade assembly, as shown and described.

DESCRIPTION

FIG. 1 is a perspective view of a mower blade assembly showing our new design;

FIG. 2 is another perspective view thereof;

FIG. 3 is a top plan view thereof;

FIG. 4 is a bottom plan view thereof; and,

FIG. 5 is a side elevational view thereof.

The broken lines depict portions of the mower blade assembly that form no part of the claimed design.

1 Claim, 3 Drawing Sheets

Related U.S. Application Data

No. 17/573,153, filed on Jan. 11, 2022, which is a continuation of application No. 17/236,239, filed on Apr. 21, 2021, now Pat. No. 11,246,260, which is a continuation of application No. 17/164,479, filed on Feb. 1, 2021, now Pat. No. 11,122,737, which is a continuation of application No. PCT/CN2019/107650, filed on Sep. 25, 2019.
